UNITED STATES PATENT OFFICE.

HALBERT B. HALVORSEN, OF MICHIGAN CITY, INDIANA, ASSIGNOR TO SULLIVAN MACHINERY COMPANY, A CORPORATION OF MASSACHUSETTS.

FORGING MACHINE.

Application filed April 20, 1925. Serial No. 24,420.

This invention relates to forging machines, and more particularly to a machine for forging coal mining machine cutter bits.

In a forging machine of the type herein disclosed the bit portion of the cutter bit is forged by a roller die between which and the cutter bit or work piece relative reciprocatory movement takes place. It is desirable to forge the bits as rapidly as possible while the bit is hot, but due to certain conditions it is only possible to pass the roller over the bit during the forging stroke at a limited speed.

It is also desirable to have the actuating force for the die must effectively applied when the die is in actual forging contact with the bit.

It is also desirable to have the forging roller die which is freely rotatable present a new surface thereof during each forging stroke. While the roller may spin at the end of each stroke and thereby present a new surface, yet by my improved means employed herein the spinning action will be considerably augmented and thereby more positively insure presentation of a new portion of the surface. It is especially desirable to present this new surface for the reason that if the die rolls back and forth, each time having the same portion of its surface engaging the bit, that portion of the surface might become excessively worn, but of more immediate importance is the fact that scale or other foreign matter might adhere to the forging surface and as a result upon being successively rolled into contact with the bit would have a tendency to press the matter into the surface thereof.

It is accordingly an object of the invention to provide improved means whereby the number of forging strokes for a given length of time will be increased while retaining a normal forging speed. A more specific object of the invention is to provide an improved arrangement of a crank and connecting rod driving mechanism to effect a normal forging stroke and a quick return stroke of the forging die. Another object of the invention is to provide improved means whereby the crank shaft for actuating the die will exert its actuating force in a more direct line on the cross head carrying the die and while the latter has forging contact with the bit. More specifically an object of the invention is to provide

actuating means for the die comprising a connecting rod and crank shaft, the center of which is displaced below the plane of movement of the wrist pin connecting the rod to the forging die cross head. The single construction permits all the above functions to be performed.

In the accompanying drawings I have shown for purposes of illustration one form which my invention may assume in practice.

In these drawings, —

Fig. 1 is a side elevation of a forging machine partly broken away to show details of construction.

Fig. 2 is a diagrammatic exaggerated view showing the crank and connecting rod in the position for obtaining maximum forward movement of the cross head carrying the roller die.

Fig. 3 is a similar diagrammatic view showing the parts in position for obtaining maximum rearward movement of the cross head.

In this illustrative embodiment of the invention a base frame 1 mounted upon legs 2 and 3 carries a reciprocable crosshead 4 guided in lateral ways 5. The front end of the cross head supports a yieldably pivoted member 6 carrying in a clapper box 7 a freely rotatable forging die roller 8 having a uniform peripheral groove 9. An upwardly extending slot in a frame 10 holds a bit blank 11 during forging which causes the bit face to engage the face of a stationary die 12 which is similar in transverse configuration to the cross sectional area of the groove 8 and to the finished bit end. My improved means for reciprocating the die 8 comprises a crank shaft 13 having a crank pin 14 rotatably driven by a belt fly wheel 15 about a central axis 16 which is disposed below the horizontal plane containing the axis of a wrist pin 17 which connects a rod 18 carried by the crank pin 14 to the crosshead 4. In Figs. 2 and 3 the center 16 of the crank is diagrammatically shown considerably below the line of movement of the wrist pin 17, it being noted that when the crank is on the right hand side of its center and in line with the connecting rod 18, the crosshead 4 will be at its maximum forward position. When the crank is at the left hand side of its center and in line with the connecting rod 18 the crosshead will be in its maximum rearward position. In these respective posi-

tions the angle A is considerably less than the angle B and accordingly movement of the crosshead from the position shown in Fig. 2 to that shown in Fig. 3 will take place during rotation of the crank through an angle less than 180 degrees which is determined by the difference between angles A and B. Thus forward movement of the crosshead takes place during movement of the crank through an angle of 180 degrees plus the above difference. Accordingly, uniform crank shaft rotation causes the crosshead to move rearwardly faster than forwardly. The result is that the crank shaft rotation can be brought up to such a speed as to impart a normal rate of forward movement of the die for forging operations. Thus a greater number of strokes will be made by the crosshead in a given length of time. Accordingly, bits may be quickly forged before the heat therein is dissipated resulting in a greater quantity of better forged bits. By having the crank center disposed below the line of movement of the wrist pin 17 the crank pin 14 will, when in a vertical position, about the time the die engages the bit, be more nearly in a plane containing the path of movement of the crosshead than if the crank center were in said plane, and accordingly exerts an actuating force in more of a direct line to the crosshead at the time most needed. Due to the quick return the roller die is more apt to be given a quick spinning action due to dragging engagement with the bit and die 12 than if the die moves at the same rate on both strokes, the advantages of which have been previously discussed.

While I have in this application specifically described one form which my invention may assume in practice, it will be un-

derstood that this form of the same is shown for purposes of illustration and that the invention may be modified and embodied in various other forms without departing from its spirit or the scope of the appended claims.

What I claim as new and desire to secure by Letters Patent is:

1. A cutter bit forging machine comprising a roller forging die and cutter bit supporting means, and means for causing relative reciprocatory rectilinear movement therebetween including a crank shaft and connecting rod adapted when in alinement to be disposed at an angle to the path of relative movement.

2. A cutter bit forging machine comprising die means, a cutter bit support, and means for causing relative reciprocatory rectilinear movement therebetween including a crank and connecting rod adapted to cause normal forging movement and a higher rate of return movement.

3. A cutter bit forging machine comprising a rectilinearly reciprocable crosshead carrying at its respective ends a roller forging die and a connecting rod, a crank shaft connected to said rod and having its axis of rotation offset from the line of movement of the rod connection to the crosshead.

4. A cutter bit forging machine comprising a crosshead carrying forging die means movable in a straight line, and a crank and connecting rod for actuating the same disposed to the rear thereof, said crank being so disposed as to impart at the moment of forging an actuating force to said crosshead in substantial alinement with the path of movement thereof.

In testimony whereof I affix my signature.
HALBERT B. HALVORSEN.

Certificate of Correction.

Patent No. 1,633,742.

Granted June 28, 1927, to

HALBERT B. HALVORSEN.

It is hereby certified that error appears in the printed specification of the above-numbered patent requiring correction as follows: Page 1, line 15, for the word "must" read *most*; page 2, line 21, for the word "in" read *is*; and that the said Letters Patent should be read with these corrections therein that the same may conform to the record of the case in the Patent Office.

Signed and sealed this 18th day of October, A. D. 1927.

[SEAL.]

M. J. MOORE,
Acting Commissioner of Patents.
